UNITED STATES PATENT OFFICE.

PAUL E. DIEDERICH AND MARSHAL G. ROBERTS, OF DETROIT, MICHIGAN, ASSIGNORS TO AMERICAN INJECTOR COMPANY, OF DETROIT, MICHIGAN, A CORPORATION OF MICHIGAN.

AUTOMOBILE HEATER.

Application filed September 29, 1927. Serial No. 222,711.

This invention relates to the construction of automobile heaters, and has for its object a construction adapted for use in connection with the exhaust pipe of such engines as are 5 at present installed on Chevrolet automobiles, and also to provide simple and efficient means to take a sufficient amount of heat from the exhaust gases for the heating of the body of the automobile.

10 This invention consists in the details of construction illustrated in the accompanying drawing, wherein Fig. 1 is a side elevation of an engine equipped with a heater embodying the present invention. Fig. 2 is a plan 15 thereof. Fig. 3 is a vertical section on the line 3—3 of Fig. 2 on a larger scale. Fig. 4 is a section on the line 4—4 of Fig. 3.

Similar reference characters refer to like parts throughout the several views.

20 A very common type of automobile heater consists of a shell enclosing the exhaust manifold and provided with an air inlet at its front end and a pipe connecting at its rear end to carry heated air to the body of the 25 automobile. It sometimes happens that it is impossible, or at least undesirable, to use this type of heater, and we have designed a heater of the type shown in the present drawing, which is quite effective and satisfactory 30 for many automobiles.

The body of the heater comprises two flat sides 1 and 2 of any convenient shape, between which a curved pipe 3 is held by means of removable transverse plates 7, 5, and 6 35 whose side edges are bent at right angles so they may be bolted to the plates 1 and 2. The sides 1 and 2 may be of any desired and convenient shape. The adjacent edges of the plates 7 and 6 are cut to fit the pipe 3. A continuous strip 4 of metal extends substantially 40 around the remaining open edges of the sides 1 and 2 to a gap 8 through which air may pass into this heater, this strip 4 being attached to the sides 1 and 2 in any desired 45 manner. When the heater is positioned on an engine, the gap 8 should be just back of the fan 10.

The side 2 is formed with an opening 12 and over it is attached a discharge connection 13, from which a conductor pipe 14 extends to the body of the automobile, a regulating device 15 of any desired type being attached to the discharge end of the pipe 14.

Engines of this character are often provided with an elbow 17 extending from the 50 exhaust manifold 18 or from passages within the cylinder block, to the exhaust pipe 19. This elbow is disconnected from the exhaust pipe and is positioned to connect to the end 20 of the pipe 3. The other end 21 of this 55 pipe 3 is connected to the exhaust pipe 19. These connections may be made before or after the casing is mounted on the pipe 3 after which the pipe 14 is installed to connect the heater to the body of the automobile.

60 The dimensions of a heater of this character and the proportions and shape of its parts may all be changed by those skilled in the art. A heating element 3 of drawn tubing 65 may be made quite thin and the transfer of heat from the exhaust gases to the surrounding air greatly facilitated.

We claim:—

A heater adapted to be attached to an internal combustion engine comprising a 70 casing formed of parallel sides and a connecting plate extending between the edges thereof, a tubular loop within the casing, removable plates closing the space between the sides and engaging the ends of said loop 75 to position it within the casing, an opening being left between the sides to admit air driven toward said opening by the fan of the engine, said loop being adapted to connect to the exhaust manifold and to the exhaust 80 pipe of an internal combustion engine, and a conductor pipe connected to one of said sides and adapted to convey heated air from the casing.

PAUL E. DIEDERICH.
